MIXING TANK

Otto Thiel, Detroit, Mich.

Application July 7, 1944, Serial No. 543,841

1 Claim. (Cl. 137—21)

This application relates to mixing tanks and more particularly to a check valve construction thereof, shown in the appended drawing whose

Figure 1 is a top plan view and whose

Figure 2 is a section on line 2—2 of Figure 1.

The drawing shows a mixing tank 10 having its upper end closed by a head 11 having lines 12, 13, and 15 connected to it.

The head is formed as a casting with three separate bosses for the various lines, the boss 20 for the water inlet line 12, the boss 21 for the gas inlet line 13, and the boss 22 for the mixture outlet line 15. The bosses 20 and 21 are connected respectively by transverse bores 23 and 24 to check valves which are disposed directly in the head. The boss 22 opens directly to the inside of the head, that is the underside.

Figure 2 shows the head casting 11 which has a boss 25 into which opens a water outlet line 27. The bore 23 is shown as opening into the inside of a well 28 formed integral with the head casting.

Disposed in well 28 is a check valve construction which as shown includes a cover casting 30 with which is integral a sleeve 31, inside which is one of two closing plugs 32. The upper ends of these closing plugs are spherical and circular in cross section and contour and the lower ends are conical to form needle valves, the circular and spherical upper ends permitting the lower ends to move slightly off the center line and find their own seats. A sleeve 33 is threaded at its upper end into the lower end of sleeve 31. A third sleeve 34 has its upper end threaded at 35 into the lower end of sleeve 33. The sleeves 34 and 33 clamp rubber sealing rings 36—37 against the sleeves 33—31. At 39 is a strainer fixed to sleeve 34.

The entire assembly of the cover casting 30, which carries sleeves 31, 33, and 34, rings 36 and 37, plugs 32, and strainer 39, forms a unitary assembly which may be dropped into the well 28 and is accessible merely by loosening a few cap screws 43 accessible at the top of the head.

The cover casting 30 has a transverse bore 44 which connects the interior of the valve to the line 27.

The flow path for water is as follows:

It comes into the tank through line 12, boss 20, bore 23, and it enters the well 28 and goes down around the lower sleeve 34 and enters that lower sleeve 34, moving upwardly at the arrow 45, going through the strainer 39, and past the lower end of the lower plug 32 and then up past the lower end of the upper plug 32 and then into the bore 44 of the casting 30 and then down through the outlet line 27, to the bottom of the tank.

Now having described the check valve construction herein shown, reference should be had to the claim which follows.

I claim:

A mixing tank having a tank head to which is connected an inlet fluid line, and a check valve construction within the head, the check valve construction being a unitary structure removably disposed within the head, and removable from or applicable to the head as a unit, without requiring removal or disturbance of the head or the line connected to it, the head having an integral, depending, open top, closed bottom well into which the inlet line opens, and the check valve construction comprising a cover for the well, the cover having as part thereof a depending sleeve dipping into the well, said sleeve being open at its top and bottom, the cover having a bore opening to a surface thereof and thus to the tank interior and also opening to the upper end of the sleeve, and a gravity check valve plug within the sleeve for closing it against down flow into the well from the cover bore, the plug being held in the sleeve by restrictions at its upper and lower ends, the valve responding for closing to pressure in the tank exceeding that of the inlet line.

OTTO THIEL.
